L. SCHEFF

KNOCKDOWN BOAT

Filed Aug. 18 1924

Inventor.
Bernard Scheff
By Harry F. Teller, attorney.

UNITED STATES PATENT OFFICE.

LEONARD SCHEFF, OF HUNTINGTON LAKE, CALIFORNIA.

KNOCKDOWN BOAT.

Application filed August 18, 1924. Serial No. 732,626.

To all whom it may concern:

Be it known that I, LEONARD SCHEFF, a citizen of the United States, residing at Huntington Lake, in the county of Fresno 5 and State of California, have invented certain new and useful Improvements in Knockdown Boats, of which the following is a specification.

This invention relates to a knockdown boat preferably of a type designed particularly for pleasure seekers, explorers, and fishermen.

The principal objects of the invention are to provide a light weight sectional boat 15 adapted when in knock-down condition to occupy but small space and capable of being easily transported in a pleasure motor vehicle or by a small trailer; one which is capable of being easily assembled, and where- 20 in the joints between the sections are maintained water tight, and wherein the means for maintaining the sections in assembled relation affords a plurality of braces longitudinally of the hull at spaced points 25 throughout its full length.

The invention consists primarily in a plurality of metallic, preferably aluminum, hull sections, including intermediate and end sections adapted for nesting when disassembled 30 to provide a compact structure requiring but little space in transporting, sections having interlocking connection at adjacent edges, there being provided a keel, and there being provided flexible uniting members secured 35 to one end section and engageable with the other end section whereby the same extend longitudinally of the hull at spaced points on its outer surface, and there being further provided a means for maintaining the flexible uniting members under tension.

With the above mentioned and other objects in view, the invention consists in the novel construction and combination of parts hereinafter described, illustrated in the accompanying drawings, and set forth in the claims hereto appended, it being understood 45 that various changes in the form, proportion, size and minor details of construction within the scope of the claims may be resorted to without departing from the spirit or sacrificing any of the advantages of the invention.

In the drawings disclosing one embodiment of my invention:

Figure 1 is a view in side elevation of the preferred embodiment of my knock-down

boat illustrating the sections in assembled relation.

Figure 2 is a view in top plan of the interior of the boat with the seats or thwarts 60 removed.

Figure 3 is a view in elevation of the stern of the boat.

Figure 4 is a section on line 4—4 of Figure 1 illustrating a detail of the keel. 65

Figure 5 is a fragmentary detail view of the takeup connection of the free end of the flexible uniting member.

Figure 6 is a perspective detail of a gunwale section taken on line 6—6 of Figure 1 70 illustrating the tubular channel, extending longitudinally of the terminal side edge of each section and through which one of the uniting members extends.

Figure 7 is a perspective sectional view on line 7—7 of Figure 2 illustrating one of the interlocking joints, and

Figure 8 is a transverse sectional view through the boat on lines 8—8 of Figure 1.

In the drawings wherein like characters of reference designate corresponding parts, the boat is indicated generally by the numeral 1, and the same consists of a hull formed of a plurality of one piece metallic hull sections 2, preferably of aluminum. The upper edges of the hull sections are bent over into tubular formation as at 3. The transverse rear edge of each intermediate hull section and the edge of the bow section 4 is each preferably bent outwardly and backwardly on itself as at 5, and the remainder of the material is in turn bent to lie in parallel spaced relation exteriorly of the back bent portion 5 as at 6 with its terminal edge 7 lying substantially flush with the crease 8. 85 This bend extends for the full transverse length of each section and provides an interlocking pocket or joint 9, within the base of which is preferably positioned a body of suitable calking material 10. The forward edge of each intermediate section 2 and the edge of the stern section 11 is bounded by a relatively flat reinforced strip 12 retained in position by bending over the free edge 13 of each section as in Figure 7. This form 90 of construction provides a water tight joint between the assembled sections, and the respective joints open toward the stern of the boat and are not subject to the water pressure when the boat is being propelled forwardly through the water. Each section 2 and the bow and stern sections 4 and 11 are

provided with the well known keel portions 14, the adjacent ends of which are adapted to abut when the hull sections are in assembled relation as in the drawings. The keel sections are longitudinally grooved as at 15, as illustrated in Figure 4.

To provide a means for affording a plurality of braces longitudinally of the hull and to retain the hull sections in assembled relation with the calkings 10 under compression, I prefer to employ a plurality of flexible cables or members 16 each preferably secured to the bow section 4, flexible members or cables being illustrated as five in number. One member 16 is disposed to extend longitudinally of the keel 14 and to be received in the groove 15 therein, and two other members are attached to the bow section of the boat to extend in a straight line rearwardly therefrom substantially parallel with the load water line, and two others, those termed the gunnel cables are each one adapted to pass through the tubular portions 3. Each cable when in assembled position is adapted to be drawn tight, and to facilitate this tightening at its free end carries a threaded member 17, and these threaded members are adapted for reception within apertures in the plates 18 disposed radially of the stern-board 19 of the stern section 11, and to receive the takeup members 20 illustrated in the form of winged nuts. The assembling of the parts as indicated in the drawings and the disposal of the cable 16, as illustrated, enables the sections during their assembly to be maintained with their interlocking edges one received within the other and with the cables affording braces longitudinally of the hull for its full length exterior of the hull forming plates.

When it is desired to knock down the boat, it is only necessary to release the nuts 20, withdraw the flexible cable 16, separate the sections 2, 4, and 11, and nest the same for transporting.

I claim:—

1. A knock down boat including a metallic hull divided transversely into a plurality of nestable sections, the metal at one transverse edge of each intermediate section being bent backwardly upon itself and thence forwardly in substantially parallel spaced relation to the back bend to provide an edge receiving channel extending substantially the full length of one transverse edge, the opposite transverse edge being provided for its full length with a reinforced member, a calking in the base of the channel, and means for detachably securing the sections into boat forming position.

2. A knock down boat including a metallic hull divided transversely into a plurality of nestable sections, the metal at one transverse edge of each intermediate section being bent backwardly upon itself and thence for-

wardly in substantially parallel spaced relation to the back bend to provide an edge receiving channel extending substantially the full length of one transverse edge, the opposite transverse edge being provided for its full length with a reinforced member, a calking in the base of the channel, and means for detachably securing the sections into boat forming position, said means affording a continuous brace at spaced points longitudinally of the boat.

3. A knock down boat including a metallic hull divided transversely into a plurality of sections adapted for separation from each other, an interlocking calked connection between the cooperating edges of adjacent sections, a plurality of flexible tie members secured at one end to one terminal boat section for extending longitudinally of the exterior of the hull on the assembling of the sections, and means for attaching said tie members to the other terminal boat section and for drawing the same taut.

4. A knock down boat including a metallic hull divided transversely into a plurality of sections adapted for separation from each other, an interlocking calked connection between the cooperating edges of adjacent sections, a plurality of flexible tie members secured at one end to one terminal boat section for extending longitudinally of the exterior of the hull on the assembling of the sections, and means for attaching said tie members to the other terminal boat section and for drawing the same taut, said tie members affording a plurality of braces longitudinally of the boat at spaced points on the exterior of the hull.

5. A knock down boat including a metallic hull divided transversely into a plurality of nestable end and intermediate sections, the metal for substantially the whole length of one transverse edge of each intermediate section and the one transverse edge of one end section being bent outwardly and backwardly on itself and thence forwardly in substantially parallel spaced relation to the back bend, to provide an open-ended receiving channel, the metal for substantially the whole length of the other transverse edge of each intermediate section and the edge of the other end section being bent outwardly to provide a pocket, a reinforcing member held within the pocket, a calking in the base of the channel, a plurality of flexible tie members secured to one end member, devices associated with the other end member for receiving the free ends of the tie members, and take-up means associated with the tie members for maintaining the same taut when the boat sections are in assembled position.

6. A knock-down boat including a hull divided transversely into a plurality of sections adapted for separation from each

other, an interlocking connection between the co-operating edges of adjacent sections, a plurality of flexible, tight members secured at one end to one terminal boat section 5 for extending longitudinally of the hull on the assembling of the sections, and means for attaching said tight members to the other terminal boat section and for drawing

the same taut, said tight members affording a plurality of braces longitudinally of the 10 boat hull to maintain the sections with their edges in co-operating relation.

In testimony whereof I have signed my name to this specification.

LENARD SCHEFF.
